PRINTING TELEGRAPH APPARATUS

Raymond E. Zenner, Brookfield, Ill., assignor to
 Teletype Corporation, Chicago, Ill., a corpora-
 tion of Delaware

Application May 25, 1936, Serial No. 81,548

13 Claims. (Cl. 178—4)

This invention pertains to printing telegraph apparatus and more particularly to tabulating mechanism for such apparatus.

In printing telegraph systems employing recording apparatus provided with tabulating mechanisms, time is necessarily required to move the type carriage or platen carriage from one position to another during tabulation. In manual operation of key controlled recording apparatus, cognizance is taken of the tabulating time by the operator who, during such time, refrains from further operation of the keyboard. However, in automatic operation of such recording apparatus, by means of tape transmitters, in which case the apparatus is unattended for extended periods of time, it is desirable to simulate manual control during tabulation so as to suspend transmission automatically during the time that the carriage is in motion while tabulating, thus preventing the false operation of the recording apparatus.

The salient object of the present invention is to provide for suspending signal transmission during tabulation operations in response to a condition established in a transmitter.

Another object of the invention is to provide means for automatically interrupting the transmission of signals from a transmitting distributor during tabulation which is controlled primarily from the transmitting distributor and secondarily from the transmitter-control printer.

A feature of the invention resides in providing an extra set of contacts in a tape transmitter to be controlled by the tape sensing elements simultaneously with the control of the normally operated transmitting contacts. The sensing of a tabulation code combination in the tape not only causes the tabulation code signal to be transmitted to the receiving printer, but also causes the extra set of contacts to establish simultaneously an energizing circuit for a transmitter cut-out relay, which will remain energized during the tabulation period, whereupon by the opening of a contact in the receiving printer under the control of the tabulating mechanism therein, the energizing circuit for the cut-out relay is broken to initiate again the transmission of code signals.

The above and other objects of the invention are accomplished by the provision in a printing telegraph apparatus, of the type disclosed in U. S. Patent No. 1,904,164, of a tabulator bar which extends across the front of the machine and is carried by brackets mounted in the typing unit and capable of swinging toward and away from the

type carriage. The tabulator bar carries a number of adjustable stop-control members which determine the positions to which the type carriage is automatically spaced a plurality of character spaces upon the reception of a tabulator code signal combination. The spacing mechanism of the printing apparatus comprises a multi-toothed ratchet adapted to cooperate with a pair of pawls which are actuated by the printing bail to function as an escapement mechanism, so that upon each revolution of the main shaft, the spacing worm gear associated with the spacing ratchet is permitted under normal operating conditions to escape one tooth at a time and hence to rotate through a corresponding angle.

According to the aforementioned patent, a series of function levers is provided which operate in accordance with the setting of the series of selector vanes. Within this series of function levers, the present invention contemplates the provision of a tabulating function lever which, when selected, is drawn forward into the selector vanes under spring tension. When this occurs, the rear extension of the function lever raises and thereby lifts the rear end of a horizontal lever member. When the rear end of this horizontal lever is raised, it lifts, through suitable linkage, the upper spacing pawl out of engagement with the tooth of the spacing ratchet, at which time the front end of said horizontal member is lowered, thereby unlatching the tabulating bar to permit the latter to be biased by its spring toward the type carriage. When the upper space pawl is thus disengaged, the lower space pawl returns to its normal position free of the teeth on the spacing escapement ratchet which permits the spacing worm to make one complete revolution instead of only one-third of a revolution during the time that the main shaft rotates through one revolution, and therefore the carriage will be spaced continuously a distance, per revolution of the main shaft, which is three times that of normal spacing distance.

To bring the carriage to rest after tabulating, it is necessary to permit the upper space pawl to drop again into engagement with a tooth on the spacing ratchet. This latter function is effected by the coaction of a cam element assembled to the carriage and one of the adjustable stop-control members carried by the tabulator bar. This cam forces or cams the tabulator bar forward or away from the carriage, against spring tension, and in so doing permits said horizontal member to be restored to its normal position into latching engagement with the tabulator bar. This

restoration action of the horizontal member permits the upper space pawl again to fall into engagement with a tooth on the spacing ratchet, which thereupon brings the carriage to rest.

5 During the time in which the carriage is moving automatically from stop to stop during tabulation, it is necessary to suspend transmission of signals to the printer, and accordingly the present invention provides an arm depending from the 10 tabulator bar which cooperates with a bell crank lever to control a contact in the operating circuit of a cut-out relay in the tape transmitting distributor. In this operating circuit is also included the aforementioned extra set of contacts, 15 associated with and controlled by the tape sensing levers in said distributor, which are so wired or connected together that whenever said tape sensing levers assume a particular setting in response to a predetermined code combination of perforations in the tape, said set of contacts will complete a series circuit including said contact in the printer, said set of contacts, and said cut-out relay. Thus, when the tabulation code signal is sensed by the sensing levers, the transmitter will 25 cease to operate upon the completion of transmission of the tabulator signal, due to the opening of the start magnet circuit of the transmitter under control of the cut-out relay, and the tabulator mechanism in the receiving apparatus will 30 function in response to the tabulation signal to permit the type carriage or platen carriage, as the case may be, to travel uninterruptedly to the next stop control member, whereat the tabulator bar will be cammed outwardly to cause the restoration 35 of said tabulator mechanism to normal, and simultaneously, through the cooperation of said depending arm and said bell crank, the contact controlled by said bell crank will be opened momentarily so that the operating circuit for 40 said cut-out relay will be broken to permit the transmitting distributor again to operate.

A better understanding of the invention may be had from the following description, taken in conjunction with the accompanying drawing, 45 wherein,

Fig. 1 is a front elevational view of the principal portion of the printing apparatus showing the application of the tabulating mechanism thereto, supplemented with a schematic circuit diagram illustrating the relation between the transmitting distributor and the transmitter-control printer;

Fig. 2 is a transverse sectional view of the printer taken approximately on line 2—2 of Fig. 1;

Fig. 3 is a cross-sectional detail view taken approximately on line 3—3 of Fig. 1;

Fig. 4 is a sectional detail view taken on line 4—4 of Fig. 1; and

60 Fig. 5 shows the manner in which the switches of the tape transmitter are controlled by the tape sensing levers.

In the accompanying drawing, like reference characters indicate similar parts throughout the 65 several figures. For a complete understanding of details not disclosed herein and which form a part of the present invention, reference should be made to U. S. Patent No. 1,904,164 issued April 18, 1933 to S. Morton et al.

70 Briefly, having reference to Figs. 1, 2, and 3, a printing apparatus to which the tabulating mechanism of the present invention is applied comprises a typing unit (indicated generally in Fig. 1) which includes a primary selecting mechanism of which only the single selector magnet 11

is shown in Fig. 1 and which is of the sword-and-T-type disclosed in U. S. Patent No. 1,745,633 to S. Morton et al. (fully disclosed in the first mentioned patent), and a secondary selector or selector vane assembly indicated generally as 12. 5 The selector vane assembly 12 controls through a set of bell cranks 13 (Fig. 1) a corresponding set of curved code bars 14 carried in a movable type carriage indicated generally at 15. As set forth in the first mentioned patent, this type carriage 10 is movable longitudinally with respect to a stationary platen not shown, but manifestly the invention is not limited in its application to such apparatus.

Referring particularly to Fig. 2, a motor (not shown) supplies power to a main operating shaft 16 which carries the spacing mechanism indicated generally 17 as well as the selector cam assembly (not shown) which cooperates with the selector magnet 11. The spacing mechanism 17 controls through gear 18, shaft 19, gear 21, and rack 22 (Fig. 2) the successive advancement of the type carriage 16 to form character spaces, tending in this movement to wind up a carriage return spring mechanism (not shown) which is 25 effective upon the receipt of the carriage return signal to effect, due to the energy stored up in said spring, the return of carriage 15 to its normal beginning-of-line position.

Parallel to the main operating shaft 16 is an auxiliary shaft 23 on which are carried various mechanisms, for example, printing bail 24, function lever bail 25, and the escapement elements of the spacing mechanism 17. The printing bail 24, which is actuated by a spring 20 at the proper time in the operative cycle, functions to reciprocate a pull bar operating member 26 to cause, through a pull bar 27, the operation of a particular type bar 28.

The selector vanes 88 control a series of function levers among which, and provided especially for accomplishing the object of the present invention, is a tabulating function lever 29 which, like the other function levers, is pivoted on a common pivot rod 31 and is assembled in a slot 40 in the function lever comb 32. Function lever 29, like the rest of the function levers of the series, is provided with an individual spring 33 tensioned between the lever and the printer frame, thus tending to rotate the function lever 29 clockwise 45 about pivot 31. However, the biasing of lever 29 is restrained by the function lever bail 25 acting through rod 34 on arm 35. Function lever 29 is provided on its arm 36 with code notches and projections which cooperate with the vanes 45 of the selector vane assembly 12 and which are coded to correspond to the tabulator signal.

In Fig. 2 there is shown mounted on the main shaft 16 a sleeve member 37 which comprises integral therewith a ratchet 38 and a spacing worm 60 39 which meshes with gear 18. Sleeve member 37 is operably connected to the shaft 16 by means of a friction clutch (not shown), and through which it is rotated by main shaft 16, unless blocked by the pawls of the spacing mechanism 65 17, as will presently appear.

Referring to Fig. 2, it will be noted that ratchet 38 is provided with three teeth 41, 42, and 43, the escapement of which will allow the type carriage 15 to be moved forward one step or character space for each actuation of the printing bail 24. As indicated, the escapement mechanism comprises a pair of pawls or levers 44 and 45 pivotally mounted on shaft 23 and a lever 46 carried by the printing bail 24. Spring 47 nor- 75

5 mally tends to bias levers 44 and 45 attrahently, since it is common to both levers. Lever 44 is normally urged by spring 47 in a counterclockwise direction so that its laterally disposed end 48 engages tooth 41 of ratchet 38, thus arresting the rotation of said ratchet. Lever 45 is normally held out of engagement with ratchet 38, opposing the tension of spring 47 by the intervention of lever 46 whose free end extends into 10 the path of laterally disposed end 48.

10 Lever 46 is pivotally connected at 51 to printing bail 24 and is provided at 52 with a slot and screw adjusting means, whereby, in well-known manner, the correct relative position of escapement levers 44 and 45 with respect to ratchet 38 may be determined. The spacing operation occurs immediately following or subsequent to the printing of a character in the following manner.

20 To print a character, the printing bail 24 oscillates, and in so doing controls the operation of lever 46. During the initial portion of the clockwise movement of arm 46, lever 44 under the action of spring 47 also rotates clockwise to bring the laterally disposed end 53 into the path of tooth 42. It is noted that, due to the space indicated at 54 between lever 46 and laterally disposed end 55 of lever 44, the latter will not be acted upon, and end 48 thereof remains in engagement with tooth 41. However, upon the further clockwise movement of lever 46, the end of arm 55 is encountered and for this reason similar movement is then imparted to lever 44, effecting the disengagement of end 48 from tooth 35 41 and permitting ratchet 38 to rotate slightly in a clockwise direction under the influence of friction clutch members which are situated between sleeve 37 and shaft 16. This motion is limited by the engagement of tooth 42 with laterally disposed end 53 of lever 45, which lever, as was noted, was free to rotate in a clockwise direction under the tension of spring 47 into the path of oncoming tooth 42. Ratchet 38 is thus restrained from rotation by lever 45 while the character is being printed, after which time, printing bail 24 and associated lever 46 rotate in a counterclockwise direction actuated by a printing cam (not shown) carried on shaft 16. Restraint upon lever 44 by lever 46 through end 50 55 is thereby removed, permitting lever 44 to rotate in a counterclockwise direction under the influence of spring 47 into the path of oncoming tooth 43 of ratchet 38. During this counterclockwise movement of lever 46, and after the aforementioned removal of restraint upon lever 44, lever 45 is caused to rotate in a like direction due to the action of lever 46 on laterally disposed end 49 thereof, thereby disengaging end 53 of lever 45 from tooth 42 and allowing ratchet 38 to continue its rotation until arrested by the engagement of end 48 of lever 44 with tooth 43. It is observed that as a result of the escapement mechanism just described, there is a period of overlap during which ends 48 and 53, due to the space indicated at 54 are effective simultaneously to prevent the escapement of ratchet 38, the ends 48 and 53 being otherwise alternately engageable to permit the escapement of ratchet 38.

70 It is obvious that since spacing worm 39 and ratchet 38 are integrally connected to sleeve 37, the worm 39 will have normally the same intermittent or step-by-step motion as was hereinbefore seen to be imparted to ratchet 38. Worm 39 is meshed, as previously mentioned, with worm

5 gear 18 which is rotatable on vertical shaft 19 and may be operably connected thereto through the instrumentality of a jaw clutch 56. Worm 39 and gear 18 are so related, according to the present embodiment, that one-third revolution of worm 39 will rotate gear 18 through a distance which, through gear 21 and ratchet 22, causes the type carriage 15 to be advanced the distance of one character space.

10 From the foregoing it will be observed that character spacing occurs automatically with the printing of each character; that is, the spacing function is incorporated into the printing operation. It is well known that there is a code combination allotted to each type bar, but it is possible, however, to employ a code combination 15 commonly known as the space signal, which is identified with no type bar but which will nevertheless initiate the operation of the printing mechanism. Therefore, the spacing between 20 words is accomplished, when a space signal is received, in exactly the same manner as just described, except that no type bar is operated and consequently there is no character printed.

25 In accordance with the present invention, continuous spacing may be effected upon the receipt of a code combination known as the tabulating signal, the function of which is to initiate the operation of the tabulating mechanism. The mechanically operating tabulating arrangement 30 of the present invention comprises a tabulator bar 61 extending across the front of the printing apparatus as shown in Fig. 1, which is provided with depending portions 62 and 63 and through which bar 61 is pivotally mounted on a bracket 35 64 carried in the printer frame. Thus, tabulator bar 61 is adapted to be swingable toward and away from the type carriage 15. Bar 61 is also provided with a longitudinal slot 65 extending substantially the entire length of the bar. In 40 this slot are carried adjustably movable stop members 66 which are clamped to the bars 61 by means of screws 67 and clamps 68 (Fig. 2). As indicated in Fig. 4, these stop members 66 are usually provided with an inclined or cam portion 69, conformed to produce a quick action upon 45 cooperating with a cam element 71 carried by the type carriage 15 to terminate suddenly the tabulating operation.

50 Tabulator bar 61 is also provided, intermediate the depending portions 62 and 63 (Fig. 1) and suitably positioned relative to function lever 29, with another depending portion 72. Attached to and depending from portion 72 is a bar 73, the lower end of which is provided with an aperture 55 74 having its upper left-hand corner (as viewed in Fig. 2) conformed so as to provide a re-entrant stepped portion 75. The tabulator bar 61 normally tends to move in a counterclockwise direction, as viewed in Fig. 2, due to the action of spring 60 76 (Fig. 1).

55 Cooperating with the stepped portion 75 is one arm 77 of a lever 78 pivotally carried at 79 on a bracket 81 screwed to the function lever comb 32. The extremity of arm 77 is provided with 65 a laterally disposed portion 82 (Fig. 1) which cooperates with portion 75 of member 73. At the end of arm 83 of lever 78 is carried a vertically extending member 84, the upper end of which is provided with an open-ended slot adapted to engage a pin 85 carried by the escapement lever 44.

70 Function lever 29 is provided with a horizontal portion 86 so conformed that its extremity 87 engages the lower edge of arm 83 of lever 78 so that, when function lever 29 (upon its selection) 75

is permitted to rotate in a clockwise direction under the action of its spring 88 upon the proper setting of the vanes 88 in response to the tabulator code signal, the end 87 thereof is raised, causing lever 78 to rock in a clockwise direction against the tension of its spring 89. The end 82 of arm 77 is thereby moved downwardly clear of portion 75, thus permitting spring 76 to urge the tabulator bar 61 inwardly (or toward the left as viewed in Fig. 2) until wall 91 of member 73 engages portion 82. Adjustable stops 66 are therefore moved inwardly into the path of a cam member 71 (Fig. 4), which is pivoted at 92 on a portion 93 integrally formed on a bar 94, which is comparable to bar 53 shown in Fig. 1 of Patent No. 1,904,164, and which is employed for retaining the bell crank lever 13 in operable relation to vanes 88. Cam 71, like bar 94 and bell cranks 13, is movable with the type carriage 15 for carriage spacing and normally tends to rotate in a clockwise direction about pivot 92 due to the action of the spring 95, but its clockwise rotation is limited by the coaction of stop pin 96, carried thereon, with the end of bar 94. Consequently, upon the rightward movement of type carriage 15 (as viewed in Figs. 1 and 4), cam 71 due to its limited rotatability in a clockwise direction will, by its camming action on stop member 66, rock tabulator bar 61 outwardly; but upon the leftward movement of type carriage 15, cam 71 upon striking the series of stop members 66, will be rotated counterclockwise against the action of spring 95 sufficiently to avoid the cam portion 69.

Upon the clockwise rotation of lever 78 due to the selection of function lever 29, arm 83, and consequently member 84 carried thereon, will be raised, and in so doing will, through pin 85, lift escapement lever 44 out of engagement with the teeth of the ratchet wheel 38 which, since the lever 45 is (after its oscillation by bail 24) prevented from engaging the teeth of the ratchet 38 due to its being held in its retracted position by lever 46, permits the worm gear 39 to make one complete revolution instead of one-third of a revolution during the time that the main shaft 16 rotates through one revolution. The carriage will be spaced continuously a distance per revolution of the main shaft which is three times that of normal spacing, so long as the escapement lever 44 is held out of operative engagement with lever 38 which is maintained in this position due to the engagement of lug 82 with the under side of step portion 75. Thus carriage 15 will be moved continuously until cam 71 coacts with one of the series of stops 66, when through stop 66 cam 71 will urge tabulator bar 61 outwardly or in a clockwise direction as viewed in Fig. 2 to disengage lug 82 from portion 75, whereupon lever 78 will again be rotated in a counterclockwise direction by its spring 89 into the position shown in Fig. 2. The member 84 carried on arm 83 of lever 78 will again be lowered, permitting escapement lever 44 under action of spring 47 to engage one of the teeth 41, 42, or 43 of ratchet 38.

The function lever 29, however, will be returned to its unselected position (as shown in Fig. 2), at the completion of the first revolution or cycle of operation of the main shaft 16, because of the fact that during the cycle pursuant to the reception of the tabulating signal, the function bail 25 will have been reciprocated once so that rod 34, upon the down stroke of bail 25, will permit spring 33 to urge lever 29 into cooperative relation with vanes 88 only long enough to effect the selection

and hence the resulting disengagement of pawl 44, whereafter rod 34, upon its upward or return movement, will cam the function lever 29, through arm 35 thereof, away from the vanes 88 where it will be held until the reception of another code signal.

It is manifest that during the time that the carriage 15 is moving to effect tabulation, that is from the time the tabulation signal is received up to the time when cam 71 engages the next stop 66, it is desirable to prevent the transmission and reception of succeeding character code signals inasmuch as signals sent or received during the continuous movement of the type carriage during tabulation may not properly effectuate printing. This is especially true in connection with automatic transmission; hence it is an object of the present invention to provide means for suspending the transmission of code signals during the tabulation operation. Accordingly, the tabulator bar 61 is provided with a depending tongue or portion 101 (Fig. 1) the lower end of which cooperates with a bell crank 102 pivoted at 103, Fig. 3, to a base 104. Arm 105 of bell crank 102 coacts with an insulated button 106 of a contact pair 124 mounted on a bracket 108 fixed to member 64. The pair of contacts 124 is connected in a series circuit including the extra set of contacts in the transmitting distributor. The transmitting distributor, indicated generally 111, 30 may be of the structure disclosed in U. S. patent to Kleinschmidt, No. 1,632,297, except that the extra set of contacts 124 are employed in addition to the set of transmitting contacts 112.

In the transmitting distributor 111 there is a 35 set of tape sensing elements 110 (Fig. 5) which, under the control of a tape or signal storing medium 97, controls a corresponding set of contacts 112 connected directly on one side to a source of current, and on the other through individual conductors 113 to segments 114 of the sunflower distributor 115. A second set of contacts 116 are also connected to the tape sensing elements 110 and are actuated in response to the perforations in the tape in the same manner as are contacts 112. However, unlike contacts 112 which impress current from the common source of battery upon any one of the contacts thereof that are closed, certain ones of the contacts 116 are permanently connected in series to correspond to the predetermined code combination allotted to the tabulation signal. For example, in Fig. 1, the contact portions 117 are shown by their dotted-line positions coacting with upper contacts in the first and third positions and with the lower contacts 55 in the second, fourth, and fifth positions; and when the contacts, in response to the tabulation code perforated in the tape, assume their dotted line positions, a circuit is completed from battery, through winding of transmitter cut-out re- 60 lay 118, through lower contacts 5 and 4, through upper contact 3, thence through lower contact 2 and upper contact 1, over conductor 119, through a pair of contacts 121 (controlled by a universal function lever 122, as will hereinafter appear), 65 over conductor 123, through the pair of contacts 124, to ground. The effect of this circuit will be described presently.

During the normal operation of the printer mechanism, wherein the tabulator bar assumes its 70 position shown in Fig. 2, the contacts 124 remain closed. The contacts 121 previously mentioned are controlled by a universal function lever 122 carried on the common pivot rod 31. Universal function lever 122 is also provided with a spring 75

33 which acts to bias the lever 122 toward the selector vanes 38 upon the oscillation of function lever ball 25. The universal function lever 122 is provided with no code projections so that this lever is invariably biased toward the selector vanes 38 the full distance each time the ball 25 is oscillated. The lever 122 is provided with a forwardly extending portion 127 which coacts with portion 128 of the pair of contacts 121 mounted on the base 104. It is seen, therefore, that since the universal function lever 122 is operated upon each full oscillation of the printing ball 24, contacts 121 are opened momentarily. The inner ring 131 of the transmitting distributor is connected by conductors 132 to the winding of the selector magnet 11 of the selector mechanism of the printing apparatus, and in the event that several printers are connected in series, each selector magnet 11 therein is interconnected through the line wire 134.

The relay 118, when energized upon the closing of the aforescribed circuit including contacts 116, 121, and 124, closes contact 135 and opens contact 136. The closing of contact 135 causes, simultaneously, the contacts 116 to be shunted, and a locking circuit to be established from battery, through winding of relay 118, through contact 135, over conductors 137 and 119, through contact pair 121, over conductor 128, through contact pair 124, to ground. The opening of contact 136 breaks the energizing circuit for the start magnet 138 (assuming the manual switch 139 to be closed). The deenergization of the magnet 138 causes its armature 141 to respond to the pull of its spring 142 to cause the end 143 thereof to arrest the commutator arm 144, which condition obtains to suspend transmission of signals during the tabulation period.

General operation

When the manual switch 139 is closed, a circuit is completed from battery 145, through windings of start magnet 138, over conductor 146, through manual switch 139, contact 136, and conductor 147, back to battery. The energization of start magnet 138 causes its armature 141 to be pulled up, which effects the disengagement of end 143 from the transmitting arm 144, thereby initiating rotation of the transmitting arm 144 to effect the transmission of code signals over conductor 132 in accordance with the operation of contacts 112 under the control of the perforated tape. Printing will be effected and the carriage 15 will be advanced step-by-step in response to start-stop code signals transmitted from the transmitter 111. With the platen in the "letters" or unshift position, the universal function lever 122 will be operated upon the actuation of the function bail 25, thus opening contact 121 each time a character is printed. The occurrence of a tabulation signal causes the contact portions 117 to assume their dotted line positions to effect the energization of relay 118, so that energization would merely be momentary because of the fact that universal function lever 122 would be operated and the contacts 121 would be open to break this energizing circuit. However, if the platen is in the "figures" or shift position (which is the position in which the tabulator function lever 29 is selectable) a different condition will arise. When the tabulator code signal is received with the platen in the shift position, the contact portions 117 will assume their dotted line position, and the energizing circuit for relay 118 will be completed, and since the function lever 29 is selected, the

function bail 25 will be prevented from making its full oscillation; that is, its downward movement will be prevented by the coaction of projection 148 with arm 35 of the tabulator function lever 29, thus preventing the universal function lever 122 from operating and, being governed thereby, the contacts 121 will remain closed. Relay 118 will become energized and locked up over its locking circuit which includes contact 135 (now closed). At the same time, contact 136 10 will be opened to break the energizing circuit for start magnet 138.

The selection of the tabulator function lever 29 will, through its end 87, cause lever 78 to rotate in a clockwise direction to disengage 15 (through member 84) pawl 44 from tooth 41, and at the same time, end 82 of lever 78 will be disengaged from shoulder 75, permitting tabulator bar 61 to respond to the pull of its spring 76 to bring a stop 66 into the path of the pawl 71 20 (Fig. 4). Since pawls 44 and 45 are both disengaged from the ratchet 38, shaft 16 is permitted to rotate continuously, and through worm 39, gears 18 and 21, and rack 22 will cause the carriage 15 to be advanced continuously until 25 pawl 71 reaches and actuates a cam portion 69 of the next stop 66, at which time the tabulator bar 61 will be cammed outwardly (or in a clockwise direction as viewed in Fig. 2) sufficiently 30 to permit contacts 124 to open momentarily; 35 that is, due to this camming action, a slight over-travel is imparted to the depending arm 101 so that arm 101 is actuated past its normal vertical position to the dotted line position shown in Fig. 3, and the resiliency of arm 149 of the 35 pair of contacts 124 will cause the contacts 124 to separate, thus breaking the aforescribed locking circuit for relay 118 to permit the contact 135 to open and the contacts 136 to close. The closing of contacts 136 again establishes the 40 energizing circuit for start magnet 138, permitting the transmitter arm 124 to rotate to effect the transmission of succeeding code combinations of signals.

It is therefore noted that when the tabulator 45 signal is transmitted through the proper setting of contacts 112, and contacts 116 are set correspondingly, a circuit is completed through the latter contacts and the two pairs of contacts 121 and 124 in the printer, which energizes the relay 50 118. The energization of relay 118 causes its contact 135 to close, thereby (through the medium of conductor 137) shunting out contacts 116 and 117 to establish a locking circuit for relay 118, as previously traced. When the relay 55 118 is energized, contact 136 is opened to break the circuit of the transmitter distributor start magnet 138. It is further observed that if the platen of the printer is in the "letters" or unshift position, the universal function lever 122 60 will be operated (and the tabulator function lever will remain unselected) and will momentarily open the pair of contacts 121 to break the locking circuit to the relay 118, thus permitting the transmitter distributor start magnet 138 to again, 65 after a momentary interruption, become energized. On the other hand, if the platen of the printer is in the "figures" or shift position, the tabulator function lever 29 will be selected and, since printing and spacing are blocked during 70 the performance of the tabulation operation, the universal lever 122 will not be selected (and hence will not open contacts 121) and the locking circuit for relay 118 will remain closed until the type carriage 15 has reached the next tabu- 75

lator stop 66, momentarily opening (due to the over-travel of the arm 101 by the coaction of pawl 71 and cam portion 69) the contacts 124 in the printing unit and thereby breaking the locking circuit of the relay 118.

It is understood that numerous changes may be made in the details set forth in the foregoing description without departing from the essentials of the invention or from the spirit and scope of 10 equivalency thereof, as defined in the appended claims.

What is claimed is:

1. In combination, a recorder responsive to signaling conditions, a transmitting apparatus comprising a tape transmitter, a distributor having a normal rest position, a set of tape controlled contacts normally effective to control the operation of said recorder, another set of tape controlled contacts effective in response to a predetermined signal record in the tape to control the arrest of said distributor in its normal rest position, and means in said recorder effective under certain operating conditions for restarting said start-stop distributor.
2. In a telegraph system, a transmitter having a first set of tape controlled contacts normally effective to control signal transmission, and a second set of tape controlled contacts effective in response to a predetermined signal record in the tape to establish other controlling conditions, a receiver responsive to signaling conditions comprising a functional instrumentality, and means controlled by said instrumentality and effective conjointly with said second set of contacts for controlling the effectiveness of said transmitter.
3. In combination, transmitting means effective under the control of a signal storing medium, said means having sensing means normally effective to control signal transmission, and means effective in response to a predetermined signal record in said signal storing medium as sensed by said sensing means to establish other controlling conditions, a receiver responsive to signaling conditions comprising a functional instrumentality, and means controlled by said instrumentality and effective conjointly with said second recited means for controlling the effectiveness of said sensing means.
4. In combination, transmitting means effective under the control of a signal storing medium, said means having a sensing means normally effective to control signal transmission, and means effective in response to a predetermined signal in the signal storing medium as sensed by said sensing means to establish other controlling conditions, a recorder responsive to signaling conditions, tabulating mechanism, and means in said recorder controlled by said tabulating mechanism and effective conjointly with said second recited means for controlling the effectiveness of said sensing means.

5. In a telegraph system, a transmitter having a primary and a secondary control means, a recorder having a carriage, spacing mechanism effective normally under the control of said primary means, permutation code mechanism to control operations other than recording comprising a plurality of function code levers, tabulating mechanism operative in response to the selective operation of a certain one of said levers to control, through said spacing mechanism, the advancement of said carriage through a predetermined plurality of spaces at a time, and means controlled by said tabulating mechanism and effective conjointly with said secondary means

for controlling said transmitter during the tabulation operation.

6. In a control system for printing telegraph receivers comprising a signal responsive means, means comprising primary and secondary instrumentalities, said primary instrumentality effective for controlling the free operation of said means during signaling periods, and means controlled by the telegraph receiver and effective conjointly with said secondary instrumentality 10 to render said primary means ineffective during predetermined periods.

7. In a telegraph system, a transmitter operable under the control of a tape, tape sensing mechanism comprising a primary and a secondary 15 instrumentality, a receiver responsive, through said primary instrumentality, to signaling conditions, said receiver comprising a functional agency, and means controlled by said agency and effective conjointly with said secondary instrumentality for controlling the effectiveness of said primary instrumentality.

8. In a telegraph system, a transmitter operable under the control of a signal storing medium, primary and secondary elements under the control of said signal storing medium, a receiver comprising a functional instrumentality, said receiver responsive, through said primary elements, to signaling conditions, and means effective under the joint control of said instrumentality and said secondary elements for controlling the effectiveness of said primary elements.

9. In a telegraph system, a transmitter operable under the control of a tape, primary and secondary elements under the control of said 35 tape, a receiver comprising a plurality of function members, said receiver responsive, through said primary elements, to signaling conditions, and means effective under the joint control of one of said function members and said secondary 40 elements for controlling the effectiveness of said primary elements.

10. In combination, a telegraph recorder, a carriage movable to form character spaces, spacing mechanism therefor normally adapted to 45 control the advancement of said carriage one character space, means operable in cycles to actuate said spacing mechanism normally one character space for each cyclic operation of said 50 cyclically operable means, means to disable said spacing mechanism whereby said carriage is advanced a plurality of character spaces for each cycle of operation of said cyclically operable means, a transmitter comprising a primary and a secondary instrumentality, means for controlling the effectiveness of said primary instrumentality, and means in said recorder controlled by said disabling means effective conjointly with said secondary instrumentality for controlling the effectiveness of said last mentioned means 60 during the period of disablement of said spacing mechanism.

11. In combination, a recorder having a carriage movable to form character spaces, means to perform functions other than recording, a 65 permutation device movable with said carriage to determine the character to be recorded, a stationary permutation device to control said means and said permutation device, a tabulating device controlled by said means for controlling the advancement of said carriage a plurality of spaces at a time from one recording position to another, a transmitting means controlled by a signal storing medium, said transmitting means comprising a primary and a secondary means for 75

said signal storing medium, means for controlling the effectiveness of said primary means, and means in said recorder controlled by said tabulating device and effective conjointly with said 5 secondary means for controlling the effectiveness of said last mentioned means.

12. In combination, a telegraph recorder, selector mechanism responsive to code signals, a type carriage, spacing mechanism operative normally to control the advancement of said type carriage one character space at a time, tabulating mechanism effective under the control of said selector mechanism to control the advancement of said type carriage through a plurality of spaces 10 at a time, a transmitting means effective under the control of a signal storing medium, said transmitting means comprising a primary and a secondary means for said signal storing me- 15

dium, means for controlling the effectiveness of said primary means, and means in said recorder controlled by said tabulating mechanism and effective conjointly with said secondary means for controlling the effectiveness of said last mentioned means. 5

13. In combination, a recorder responsive to signal conditions, transmitting apparatus comprising means for distributing signal impulses, a set of control elements positioned in accordance with the signal impulses to be transmitted by said distributor, means effective when said control elements are in a predetermined position for stopping said distributor, and means in said recorder effective under certain operating conditions for restarting said distributor. 10 15
